WILLIAM G. CREAMER, OF BROOKLYN, NEW YORK.

Design No. 3,442, dated April 6, 1869.

DESIGN FOR A BASKET-RACK FOR RAILROAD-CARS.

The Schedule referred to in these Letters Patent and making part of the same.

To all whom it may concern:

Be it known that I, WILLIAM G. CREAMER, of the city of Brooklyn, county of Kings, and State of New York, have originated a new Design for Basket-Racks for Railroad-Cars, of which the following is a full, clear, and exact description, reference being had to the accompanying drawings, making part of this specification.

I make my basket-racks of iron, or brass, substantially like the drawing, and between the outer and inner rim, I fill in ornamented work, of what is usually

called "The Grecian Border," and, on the inner and outer rim, I sink small panels, as shown by the dotted lines, and fill them with black-wax enamel, as shown.

What I claim as my invention, and desire to secure by Letters Patent, is—

The design for car-baskets, or basket-racks, substantially as shown by the accompanying drawings.

WM. G. CREAMER.
